UNITED STATES PATENT OFFICE.

CHARLES H. FRANCISCO, OF NEW YORK, N. Y.

DESIGN FOR A BOTTLE.

SPECIFICATION forming part of Design No. 30,264, dated February 28, 1899.

Application filed January 31, 1899. Serial No. 704,068. Term of patent 14 years.

To all whom it may concern:

Be it known that I, CHARLES H. FRANCISCO, a citizen of the United States, residing at the city of New York, borough of Brooklyn, in the county of Kings and State of New York, have invented and produced a new and original Design for a Bottle, of which the following is a description, reference being had to the accompanying drawing, forming a part thereof, which is a perspective view of a bottle embodying the features of my design.

The body A of the bottle is polygonal in cross-section. The top B is dome-shaped, and the mouth C is at one side of the top. The

longitudinal and horizontal edges D and D' of the body are serrated, and the body is decorated with a panel a and a skull and cross-bones in relief.

The leading feature of the design consists in a bottle having a polygonal body and serrated edges.

I claim—

The design for a bottle herein shown and described.

CHARLES H. FRANCISCO.
